GERMICIDAL COMPOUNDS

Carl Johnson, Maplewood, N. J., and William M.
Allison, New York, N. Y., assignors to Oakite
Products, Inc., a corporation of New York

No Drawing. Application July 27, 1935,
Serial No. 33,602

6 Claims. (Cl. 260—401)

The invention relates to germicidal compounds, and further to detergent, disinfecting and deodorizing mixtures containing such compounds.

A considerable number of materials having 5 germicidal action, and which may be used in various cleaning processes where both cleaning and sterilizing are to be accomplished in one operation, have heretofore been used. However, such materials have been unsatisfactory for various 10 reasons. For example, chlorine is frequently used but constant additions of chlorine compounds are necessary in order to maintain the germicidal property of cleaning solutions. Other materials are unsatisfactory, as they may attack 15 the articles being cleaned or have other disadvantageous properties.

One object of the present invention is to provide an odorless material to be used in cleaning which is inert to, and is not affected by, the 20 miscellaneous inert organic materials with which it comes in contact, and which acts only on bacteria and other living micro-organisms at any pH value of the cleaning solution that may be desired. There are a number of advantages in 25 a solution having such properties.

In the first place, the solutions made according to the invention remain sterile at all times and need not be used immediately after they have been made. They possess substantially the 30 same bactericidal properties at the end of the cleaning operation as at the beginning, at least if there has been no great dilution of the solution during the cleaning. Large amounts of organic matter removed during the cleaning process 35 do not appear to affect the sterilizing power of the solution.

A further advantage is that the sterilizing power may be easily determined at any time since it remains constant where there is no dilution, simply by determining the alkalinity or 40 acidity which will indicate the extent of dilution.

The materials are particularly applicable to the cleaning of bottles and the like, in which the practice is to wash with strong alkaline solutions 45 which are used for from 2 to 4 weeks. Such solutions in the usual practice contain from 3 to 5% of alkali, of which at least 60% is in the form of caustic soda. Such high concentrations 50 of alkali are required only to retard the growth of bacteria, since the cleaning alone can be accomplished by concentrations of 1% or lower. These strong alkali solutions will however react with and corrode the glass. Therefore, a further 55 object of the invention is to provide a material

which will have a minimum reaction with the articles being cleaned, and which therefore may be used with detergents of such low concentration as not to destroy the articles.

A further object of the invention is to provide 5 a material which is inexpensive and the use of which involves a relatively small amount of labor. In prior art processes, costly apparatus has been necessary to control the application of sterilizing 10 materials and methods, the materials used have been effective only for a short time, and have not been dependable.

A further object of the invention is to provide 15 a material in which considerations of temperature may be avoided, thus making accurate control of this feature of the cleaning process unnecessary.

The present invention contemplates a series 20 of new compounds which have germicidal action, and furthermore an admixture of such compounds with a detergent which results in a further increase in the germicidal power.

We have found that an organic germicide 25 which is either a base or a salt, and which is aromatic, will react with a sulfonic compound, such as a sulfonic acid or one of its salts. The reaction may take place either between an acid and a base, an acid and a salt, a salt and a base, or two salts. Preferably an aliphatic sulfonic compound is used, although the aromatic compounds will also react to produce this type of 30 product. The resulting product is obviously a sulfonic acid salt, which will not have the same corrosive effect as an alkali.

Among the materials which may be used as 35 organic germicides are aromatic mercuryl compounds which are toxic to bacteria, such as phenyl mercuric hydroxide, phenyl mercuric nitrate, phenyl mercuric chloride, para nitro toluene mercuric acetate, alpha nitro naphthalene mercuric acetate, alpha naphthyl-amine mercuric acetate, and the like. In other words, these 40 compounds are aromatic mercuryl hydroxides, or derivatives or salts thereof, which are hereinafter referred to as aromatic mercuryl compounds or 45 organic mercury germicides. The preferred compounds are those mercury germicides which have the general formula R—Hg—X in which R is an aryl radical and X is an acid radical or a hydroxyl group. The germicidal power of all 50 such compounds, and particularly of the mercuryl compounds, is increased by their combination with the sulfonic compounds.

Among the sulfonic compounds which may be 55 used, we prefer to use the aliphatic compounds

such as the aliphatic sulfonic acids, aliphatic acid sulfates, higher fatty acid amido sulfonic acids, higher fatty acid esters of sulfonated aliphatic amido compounds or the higher fatty acids altered in other ways to prevent reaction of the carboxyl group, the acid sulfates or sulfonates of the higher alcohols containing at least 8 carbon atoms and sulfonated higher fatty acids, for instance, sulfonated oleic acid, sulfonated ricinoleic acid or sulfonated abietic acid. The sodium or other metallic salts of any of the above compounds may be employed instead of the acid compounds. It is evident that other compounds of a similar nature may be used.

15 We may also use, however, the aromatic sulfonic compounds, such as aromatic sulfonic acids, substituted benzene or naphthalene sulfonates, substituted amido naphthol sulfonic acids or alkyl derivatives thereof.

20 We have found that the disinfectant materials may react with the sulfonic compounds substantially according to the following formula given by way of example:

40 The highest bactericidal activity is obtained where the two compounds to be combined are present in substantially molecular proportions, so that no excess of either remains in the product. This is particularly true where the two are added
45 to water to produce a germicidal solution for use, with or without detergents.

The process of producing these compounds may be carried out for instance according to one of the following examples:

50 1. 389 grams of methyl-oleamide-ethyl-sulfonic acid and 295 grams of phenyl mercuric hydroxide are reacted together, yielding 666 grams of methyl oleamide ethyl phenyl mercuric sulfonate and 18 grams of water.

55. 2. 238 grams of decyl hydrogen sulfate are reacted with 295 grams of phenyl mercuric hydroxide, yielding 515 grams of decyl phenyl mercuric sulfate and 18 grams of water.

3. 295 grams of phenyl mercuric hydroxide and
60 173 grams of sulfanilic acid are reacted, yielding
450 grams of phenyl mercuric sulfanilate and 18
grams of water.

4. 407 grams of amino sulfon phenyl mercuric chloride and 195 grams of sodium sulfanilate are mixed together in water. The resulting product contains 543 grams of amino sulfon phenyl mercuric sulfanilate and 59 grams of sodium chloride.

The above yields are theoretical yields which are obtainable in actual practice because the reactions involved are neutralizing reactions or double decomposition reactions resulting in the formation of water or a neutral salt. The product may be recovered by evaporating the water, alcohol, or other solvent used as a reaction medium, as any neutral inorganic salt such as sodium

chloride is not detrimental to the product. It is not necessary that the reacting materials be completely dissolved in the reacting medium as the materials will react merely by digesting them together in the specified proportions in an aqueous or alcoholic medium, after which the resulting product may be filtered and dried.

We have found that such compounds are much more effective in their germicidal action than the combined effects of the individual constituents. Tests of the constituents and of the final compounds were made in the following manner: 10

A sample of water was treated with the various mixtures, and this sample was then contaminated with some bacteria culture. It was found that the control solution contained approximately 5000 bacteria per milliliter. One milliliter of the test solution was plated in a Petri dish on nutrient agar medium for 48 hours at 37° C., and then the colonies, if any, which had developed were counted.

The following tables indicate the efficiency of the various materials so tested:

Germicide, parts per million	Count after—		
	1 minute	5 minutes	10 minutes
Methyl oleamide ethyl sodium sulfonate..... 15	1000	300	300
Do..... 20	1000	300	200
Phenyl mercuric hydroxide..... 10	200	200	100
Do..... 25	100	20	0
Methyl oleamide ethyl phenyl mercuric sulfonate..... 17	0	0	0

The following mercury compounds, due to their slight solubility, were used in the form of saturated aqueous solutions.

Germicide, parts per million	Count after—			40
	1 minute	5 minutes	10 minutes	
Trisodium phosphate and para nitro toluene mercuric acetate	7500			45
Trisodium phosphate and para nitro toluene mercuric acetate and methyl oleamide ethyl sodium sulfonate	7500	150	150	150
Trisodium phosphate and alpha nitro naphthalene mercuric acetate	7500	100	100	100
Trisodium phosphate and alpha nitro naphthalene mercuric acetate	7500	150	150	150
Trisodium phosphate and alpha nitro naphthalene mercuric acetate and methyl oleamide ethyl sodium sulfonate	7500	50	20	10
Trisodium phosphate and alpha naphthylamine mercuric acetate	7500	10	0	0
Trisodium phosphate and alpha naphthylamine mercuric acetate and methyl oleamide ethyl sodium sulfonate	7500	10	0	0

According to a further feature of the invention, we have discovered that the germicidal effectiveness of these new compounds is still further increased by admixture with a detergent, and particularly with an alkaline detergent. As suitable materials may be mentioned such alkalies or alkaline salts as caustic soda, sodium carbonate, disodium phosphate, sodium tetraborate, sodium metaborate, sodium metasilicate, and sodium orthosilicate, and corresponding potassium compounds and ammonium compounds wherever these exist. However, for certain types of cleaning operations, acids or acid salts having a detergent action may be employed, such as hydro-

chloric acid, hydrofluoric acid, sodium bifluoride, 5 sulfuric acid, sodium bisulfate, phosphoric acid, monosodium phosphate, oxalic acid, sodium binoxalate, and the corresponding potassium and ammonium salts, together with the salts of other organic acids. The preferred detergent is trisodium phosphate.

We have found that such detergents in admixture with sterilizing compounds produced according to the present invention have still greater sterilizing properties. This is indicated for example by the following table showing results of tests made in the same manner as those described in Table 1:

Germicide, parts per million	Count after—		
	1 minute	5 minutes	10 minutes
20 Trisodium phosphate 7500	2000	800	800
Methyl oleamide			
ethyl phenyl mercuric sulfonate.....	0	0	0
17 Trisodium phosphate 7500			
and methyl oleamide ethyl phenyl mercuric sulfonate.	9	0	0

Only a relatively small proportion of the germicide is necessary to reach such results. The germicide does not exceed 10%, and preferably is not over 1 or 2% of the detergent. In addition to the examples given in the table, mixtures may be provided in which the germicide and the sulfonic compound are mixed with the detergent, and permitted to react and form the new compound when the mixture is added to water for use.

In the washing of bottles in the machine generally used for that purpose, we prefer a composition having as a detergent base a mixture containing a considerable proportion of caustic soda. This mixture also contains soda ash, trisodium phosphate and, possibly, sodium meta-silicate. When a small quantity of a germicide compound produced according to the invention is added, it is possible to use such a cleansing material in a concentration of one ounce to the gallon, where four ounces have heretofore been necessary for obtaining satisfactory germicidal action. The mixture may contain as much as 60% of caustic soda.

For deodorizing, we may add compounds of the type which readily yield active oxygen (hereinafter called active oxygen compounds), such as the peracids, persulfates, peroxides, permanganates, perborates and their salts. These may be

used either with the new compounds or with the germicidal compound-detergent mixtures.

The compounds and mixtures described above are stable and effective in solutions at relatively high temperatures throughout the entire pH 5 range. In fact, their germicidal activity increases at elevated temperatures.

It is not necessary that the compounds herefore described be formed in advance of the cleaning operation. For example, the ingredients may be mixed in dry form and allowed to react only when they are dissolved in water to form the cleaning and disinfecting solution. We may for instance mix an organic germicide and a sulfonic compound, with or without a detergent and/or an active oxygen compound, in the dry state. As soon as such a mixture is added to water the materials will react to produce the new compounds.

The terms "detergent" and "alkaline detergent" as used herein are intended to mean not only the specific compounds listed above but also such mixtures and combinations thereof as may be useful for any specific cleaning process, as well as other chemical compounds, acid or alkaline, having detergent action.

The term "sulfonic compound" as used in the specification and claims is intended to cover both aliphatic and aromatic sulfonic acids and the salts thereof, and also other materials such as the acid sulfates of higher alcohols or their salts.

We claim:

1. A new organic mercury compound of the general formula $(C_6H_5H_2)_2R_1$, in which R_1 represents a radical of a higher fatty compound containing a sulfonic group.

2. A new organic mercury compound of the general formula $R.Hg.R_1$, wherein R represents an aromatic radical and R_1 represents a radical of a higher fatty compound containing a sulfonic group.

3. A new organic mercury compound of the general formula $R.Hg.R_1$, wherein R represents an aromatic radical and R_1 represents the methyl-oleamide-ethyl-sulfonate radical.

4. Methyl-oleamide-ethyl-phenyl-mercuric sulfonate.

5. A new organic mercury compound of the general formula $R.Hg.R_1$, wherein R represents an aromatic radical and R_1 represents the decyl-sulfate radical.

CARL JOHNSON.

WILLIAM M. ALLISON.
